Primary Examiner — Austin Murphy*(74) Attorney, Agent, or Firm* — Norton Rose Fulbright US LLP(57) **CLAIM**

The ornamental design for a compact brush, as shown and described.

DESCRIPTION

FIG. 1 is a top perspective view of a compact brush, with the “Mary Kay” logo and the bristle portion each illustrated in dashed lines;

FIG. 2 is a front view of the compact brush shown in FIG. 1;

FIG. 3 is a back view of the compact brush shown in FIG. 1;

FIG. 4 is a right side view of the compact brush shown in FIG. 1;

FIG. 5 is a left side view of the compact brush shown in FIG. 1;

FIG. 6 is a top view of the compact brush shown in FIG. 1; FIG. 7 is a bottom view of the compact brush shown in FIG. 1; and,

FIG. 8 is a bottom perspective view of the compact brush shown in FIG. 1.

The dashed lines in FIGS. 1-8 are included for the purpose of illustrating portions of the compact brush that form no part of the claimed design.

The “Mary Kay” trademark material illustrated in dashed lines in the Figures forms no part of the claimed design. Mary Kay Inc. is the owner of the “Mary Kay” trademark.
